UNITED STATES PATENT OFFICE

2,640,897

LIQUID BREAK CIRCUIT BREAKER

William E. Paul, Schenectady, N. Y., assignor to
General Electric Company, a corporation of
New York

Application January 3, 1951, Serial No. 204,178

7 Claims. (Cl. 200—150)

1

This invention relates to liquid break circuit breakers of the so-called impulse type, i. e. breakers in which a positive flow of insulating liquid is supplied between the contacts of the breaker during separating movement thereof for the purpose of extinguishing the arc drawn therebetween.

In this type of breaker, impulse action is ordinarily provided by means of a spring actuated piston which is movable during the opening movement of the contacts to supply a blast of arc extinguishing fluid to the arc. Pressure produced by the arc tends to impede the operating movement of the impulse piston and if the current to be interrupted is sufficiently large this pressure may even reverse the piston thereby preventing effective arc extinguishment.

In Patent 2,102,768—Trencham granted December 21, 1937, and assigned to the assignee of this invention, an arrangement is disclosed wherein provision is made for reducing or relieving the pressure set up at the contacts due to the interruption of heavy currents. In this Trencham et al. patent the pressure relieving means effectively relieves at least to some extent the pressure which tends to interfere with the piston movement but due to the action of the pressure relieving means the flow of arc extinguishing fluid toward the arc is not as positive and direct as might be required for all conditions to be encountered.

A principal object of this invention is to provide an improved impulse piston arrangement for circuit breakers wherein suitable passageways afford direct communication between the region in which the arc is formed and each side of the piston for the purpose of controlling the back thrust exerted on the piston due to arc pressure.

Another object of the invention is the provision of an improved circuit breaker of the impulse type wherein positive flow of fluid for arc extinguishing purposes is achieved without allowing arc pressure to impede the working movement of the impulse producing piston.

Still another object of the invention is to provide an improved impulse type circuit breaker wherein the operating movement of the impulse piston is substantially independent of the magnitude of the current to be interrupted.

According to the invention a piston for an impulse breaker is arranged with respect to the interrupting contacts in such a way that pressure due to the arc drawn at the contacts is effectively transmitted to both the working face of the piston and to the opposite face thereof. In

this way pressure developed due to the arc is prevented from interfering with the working movement of the piston.

The invention will be more fully understood from the following description taken in conjunction with the accompanying drawings and the features of novelty which characterize the invention will be pointed out with particularity in the claims annexed to and forming a part of this specification.

In the drawing Fig. 1 represents a side sectional view of a circuit interrupter embodying the invention, Fig. 2 is a side sectional view at right angles to Fig. 1, Fig. 3 is a cross sectional view of the arrangement shown in Figs. 1 and 2 taken along the line 3—3 of Fig. 1, and Fig. 4 is a detail view of a portion of the piston structure comprising the invention.

The interrupter unit as shown in the drawings is adapted for use in tank type circuit breakers which, as is well known, are provided with a pair of interrupting units immersed in oil contained in an enclosing tank together with a vertically movable transversely disposed bridging bar which moves into and out of engagement with each interrupting unit. Such a pair of series interrupters disposed in a common circuit breaker tank is depicted in U. S. Patent 2,513,918 to Coggeshall which is assigned to the assignee of this invention. It will be understood, however, that the invention is also applicable to other types of circuit breakers as well. For example, the principles embodied in the invention are applicable to the so-called oil poor circuit breakers of the type disclosed in Patent 2,162,583—Prince, granted June 13, 1939, and assigned to the assignee of this invention.

With reference to the drawings the interrupter unit represented therein is secured to the bottom of the entrance bushing, shown at 2 containing a conducting stud 3. Mounted at the bottom of the bushing is a flange member 4 secured in position by means of a nut 5 which cooperates with one end of the stud 3. By means of bolts 6 flanged adapter member 7 is secured to the flange 4. Adapter member 7 is provided with a downwardly extending conducting portion 8 which may be integrally formed with the top plate 9 of the interrupter unit. Enclosing casing 10, constructed of strong pressure-resistant insulating material, is secured to the top plate 9 by means of bolts 11, and bottom plate 12 of the interrupter unit is secured to the enclosing structure or casing 10 by means of bolts 13. Secured to, or formed integrally with, the top plate 9 is a

fixed contact 14 having a contacting surface 15. Movable contact 16 having a contacting surface 15a for abutting engagement with 15 is provided with downwardly extending segmental members or finger type contacts 17 which slidingly telescope with the hollow upstanding contact portion 18 shown formed integrally with the conducting bottom plate 12. The spring-driven impulse piston or fluid moving baffle 19 is adapted to carry the movable contact 16 and is provided with an indirect flow passageway therethrough comprising a vertical inlet passage 20 and a vertical outlet passage 21 interconnected at their inner ends by a cross-blast channel. Furthermore, the piston 19 is provided with a horizontal vent passage 22 the outer ends of which are arranged in registry with the elongated venting apertures 23 disposed on either side of the casing 10. Thus downward movement of piston 19 and of movable contact 16 will result in a flow of fluid from the space below the piston upwardly through vertical inlet passage 20 across the space occupied by the arc drawn between contacts 14 and 16 and upwardly through vertical outlet passage 21 into the region in the casing 10 above the piston 19. It will be observed that pressure developed in the region of the arc, after the contacts are separated, can be vented directly to the space outside the interrupting unit through the horizontal relief vent passage 22 and the registering apertures 23. The apertures 23 are made sufficiently long to accommodate the venting operation even though the piston 19 and contact 16 are in their lowermost position of engagement with the bottom plate 12. It will also be observed that whatever portion of the pressure caused by the arc which may not be quickly vented through the vent passage 22 and apertures 23 is transmitted substantially equally through the vertical passages 20 and 21 respectively to the space below the piston and to the space above the piston. The pressure caused by the arc and which is not relieved through vent passage 22 is ineffective to impede working movement of piston 19. Stated otherwise, the structure comprising the casing 10, the top plate 9 and the bottom plate 12 ordinarily would be substantially fluid tight except for the vents 23 and, by virtue of the passages 20 and 21 which afford a direct, closed means of communication between the arc and each side of the piston, any unrelieved pressure due to the arc which might otherwise tend to impede the working movement of the piston is therefore effectively counterbalanced. This does not necessarily mean that it would be desirable in every application of the invention to cause equal and opposite forces due to arc pressure to be exerted on the piston. It is conceivable that one force should be greater than the other for certain applications of the invention. To this end one of the passages such as 20 or 21 could be made larger than or otherwise dissimilar from, the other passage, or the effective piston areas could be made different, so that a predetermined differential action would be obtained.

For the purpose of compensating adverse forces affecting the piston 19, projecting guide rods 24, which are shown formed integrally with the piston, move reciprocatingly therewith through openings provided in top plate 9. These rods constitute means whereby the volumetric capacity of the casing 10 is maintained constant as the piston 19 is moved downwardly by the pull of its operating and guide rods 25 which are reciprocable through openings provided in the casing bottom

plate 12. The compensating rods 24 and operating rods 25 and their respective openings in plates 9 and 12 preferably should form substantially fluid tight seals, and it will be readily understood that as portions of the operating rods 25 move out from the casing 10, the volume thereof is not diminished by reason of the corresponding entry of the compensating rods 24 which are of like diameter.

For actuating the piston, the rods 25 are fastened into the respective ends of yoke member 26 which is provided with a central cylindrical recess 27 into the bottom of which the spring guide 28 is secured. Disposed about the guide 28 is a biasing spring 29 which engages the yoke 26 at the lower end of the spring and which engages the inner upper end of the upstanding hollow contact portion 18 of bottom plate 12. Thus it will be seen that spring 29, being a compressional spring, exerts a downward force on the yoke 26 thus biasing the piston 19 and movable contact 16 to the open position at all times.

Yoke member 26 and the above-described parts associated therewith are driven to, and maintained in, the closed position of the breaker indicated in the drawings through the agency of a striker block 30 secured, as by riveting, between the spaced ends of the paired conducting members 31 which constitute the circuit breaker reciprocable blade which bridges a pair of interrupting units of which but one is shown. Conducting blades 31 engage fixed contact fingers 32 when the breaker is closed, and it will be understood that, in the open position and after the arcs drawn between contacts 14, 16 have been extinguished, the blades 31 are widely separated from the fingers 32 for establishing an isolating gap therebetween. Yieldable means in the form of spring 3 and member 34 are interposed between yoke 26 and block 30.

The circuit through the interrupter comprises conductor stud 3, flanged plate 4, adapter structures 7 and 8, top plate 9, fixed contact 14, movable contact 16, finger contacts 17, projection 18, bottom plate 12, fingers 32, and along the blade conductors 31. A companion series interrupter of similar construction would of course cooperate with the left hand end of blade conductors 31 as viewed in Fig. 1.

In view of the description above, it will be understood that the breaker would be opened by initiating downward movement of the reciprocable blade contact 31. Such movement would permit biasing spring 29 to exert a downward force on yoke 26 which in turn would exert a downward force through rods 25 on the impulse piston 19 and arcing contact 16. Thus oil or other suitable insulating fluid would be forced from the space below the piston 19 upwardly through vertical passage 20, across the region of the arc drawn between the interrupting contacts 14 and 16, then upwardly through vertical passage 21 to occupy the space above the piston 19. Excess pressure caused by a high current arc would be relieved directly and laterally through the vent passage 22 and the vent ports 23 into the enclosing oil tank. Pressure which might fail to be relieved through this means would be exerted substantially equally both above and below the piston 19 so that, to a substantial degree any stalling action of the piston 19 and parts associated therewith from pressure unbalance is minimized. Furthermore, it will be observed that this uniform action of the piston 19 and of the parts associated therewith is achieved without

interfering with the positive flow of fluid from the space below the piston 19 into the region occupied by the arc since pressure cannot escape at any point along this closed passage.

While the arrangement shown in the drawing and described thus far utilizes a fixed contact such as 14 and a movable contact such as 16, it will be understood that both contacts could be arranged to move by any suitable known arrangement. If both the contacts were moved simultaneously the time of interruption would be reduced.

In order to facilitate closing of the contacts, vertical passages 35 best shown in Fig. 3 are provided with check valves 36 shown in Fig. 4 for the purpose of allowing the oil to flow downwardly through passages 35 as the breaker is closed. Of course the valves 36 would close due to the action of their springs 37 when the piston 19 is moving downwardly during an opening operation so as to force the oil to flow upwardly through inlet passage 20 and outlet passage 21.

While a particular embodiment of the invention only has been illustrated and described in detail, modifications thereof will occur to those skilled in the art. It is to be understood, therefore, that the invention is not to be limited to the particular arrangement disclosed and it is intended in the appended claims to cover all modifications which fall within the true spirit and scope of the invention.

What I claim as new and desire to secure by Letters Patent of the United States is:

1. An electric circuit breaker comprising casing structure containing insulating fluid, a pair of relatively movable contacts separable within said casing, means including a piston disposed within said casing and movable from a normal position to an operated position to subject the arc drawn between said contacts upon separation thereof to a flow of said fluid, said casing being substantially pressure tight in the regions thereof adjacent opposite surfaces of said piston, venting means in said casing adjacent the region in which the arc is drawn for relieving the pressure developed due to the arc, and means defining a substantially closed passageway for affording communication between the region in which the arc is drawn and said opposite surfaces of said piston so that pressure due to the arc is transmitted substantially simultaneously to said opposite surfaces.

2. An electric circuit breaker comprising casing structure substantially filled with insulating fluid, a pair of relatively movable contacts separable within said casing, means including a piston disposed within said casing and movable from a normal position to an operated position to subject the arc drawn between said contacts upon separation thereof to a flow of said fluid, said casing being substantially fluid tight in the regions thereof adjacent opposite surfaces of said piston, venting means in said casing adjacent the region in which the arc is drawn for relieving the pressure due to the arc, and means defining a substantially closed passage for affording communication between the region in which the arc is drawn and said opposite surfaces of said piston, said venting means being disposed with respect to said passage so that said opposite surfaces of said piston are substantially equally accessible to the pressure developed due to the arc drawn between said contacts so that pressure due to the arc is transmitted substantially simultaneously to said opposite surfaces.

3. An electric circuit breaker comprising casing structure containing insulating fluid, a fixed contact and a movable contact disposed within said casing, means including a piston disposed within said casing and movable with said movable contact from a normal position to an operated position to subject the arc drawn between said contacts upon separation thereof to a flow of said fluid, venting means in said casing adjacent the region in which the arc is drawn for relieving the pressure due to the arc, and means defining a substantially closed passage for affording communication between the region in which the arc is drawn and the opposite surfaces of said piston so that pressure due to the arc is transmitted substantially simultaneously to said opposite surfaces, said venting means being disposed with respect to said passage so that said opposite surfaces of said piston are substantially equally accessible to the pressure due to the arc drawn between said contacts.

4. An electric circuit breaker comprising casing structure containing insulating fluid, baffle structure disposed in said casing and movable therein from a normal position to an operated position, a passage in said baffle structure arranged so that fluid in said casing is caused to flow through said passage in response to movement of said baffle structure within said casing structure, and a pair of relatively movable contacts disposed with respect to said passage so that the arc drawn therebetween upon separation thereof is subjected to the flow of said fluid through said passage, said casing being substantially closed in the regions thereof adjacent the extremities of said passage and said passage being so proportioned that substantially equal instantaneous pressures due to the arc are transmitted through said passage to opposite surfaces of said baffle means.

5. An electric circuit breaker comprising casing structure containing insulating fluid, baffle structure disposed in said casing and movable therein from a normal position to an operated position, a passage in said baffle structure arranged so that the fluid in said casing is caused to flow through said passage in response to movement of said baffle structure within said casing structure, a pair of relatively movable contacts disposed with respect to said passage so that the arc drawn therebetween upon separation thereof is subjected to the flow of said fluid through said passage, venting means in said casing adjacent the region in which the arc is drawn for relieving the pressure developed within said baffle structure by the arc, said casing being otherwise closed so that substantially equal pressures due to the arc are transmitted through said passage to opposite surfaces of said baffle means.

6. An electric circuit breaker comprising casing structure containing insulating fluid, baffle means disposed in said casing and movable therein from a normal position to an operated position, a passage in said baffle means arranged so that fluid in said casing is caused to flow through said passage in response to movement of said baffle means within said casing structure, a fixed contact in said casing structure, a movable contact movable with said baffle means and disposed with respect to said passage so that the arc drawn between said fixed and movable contacts upon separation thereof is subjected to a flow of said fluid through said passage, venting means in said casing adjacent the region in which the arc is drawn for relieving pressure

developed by the arc, said casing being otherwise substantially closed and said venting means being disposed with respect to the region in which the arc is formed so that substantially equal pressures due to the arc are transmitted through said passage to opposite surfaces of said baffle means.

7. An electric circuit breaker comprising casing structure filled with insulating liquid, baffle means disposed in said casing and movable therein from a normal position to an operated position, spring means biasing said baffle means toward its operated position and operable to move said baffle means to its operated position during opening of said breaker, a passage in said baffle means arranged so that the liquid in said casing is caused to flow through said passage in response to movement of said baffle means toward its operated position, a pair of relatively movable contacts disposed with respect to said passage so that the

5

10

15

20

arc drawn therebetween upon separation thereof is subjected to a flow of said fluid through said passage, venting means in said casing adjacent the region in which the arc is drawn for relieving the pressure developed within said baffle means by the arc, said casing being otherwise closed and said venting means being disposed with respect to the region in which the arc is formed so that substantially equal pressures due to the arc are transmitted through said passage to opposite surfaces of said baffle means.

WILLIAM E. PAUL.
